UNITED STATES PATENT OFFICE.

PABLO A. BARBOSA, OF BUGA, VALLE, COLOMBIA, ASSIGNOR OF THIRTY PER CENT
TO ALEGANDRO VELASQUEZ, B., OF NEW YORK, N. Y.

BATTERY.

Application filed October 31, 1924, Serial No. 747,002. Renewed March 16, 1926.

To all whom it may concern:

Be it known that I, PABLO A. BARBOSA, a citizen of the United States of Colombia, South America, residing at Buga, Valle, 5 Colombia, South America, have invented certain new and useful Improvements in Batteries, of which the following is a specification.

This invention relates to dry batteries and 10 has for its object to produce a cell which will have a high amperage output, and a longer useful life than is generally obtained from cells of this type. A further object is to provide a cell in which a larger percentage 15 of the zinc and electrolyte are consumed and which will have a lower percentage of waste.

In the accompanying drawing,

Figure 1 is a longitudinal sectional view 20 of the cell,
Fig. 2 is a section showing a part of the interior in elevation, and

Fig. 3 is a horizontal section on the line 3—3 of Fig. 1.

Surrounding the central carbon electrode 25 1 is one of the usual compositions 2 consisting of powdered carbon, graphite, and manganese dioxide, contained in a suitable fabric bag 3. The bag has secured upon its surface a number of webs 4 of cardboard or heavy 30 cord, or material of a similar pliable nature. The cardboard webs are suitably secured on the bottom and top of the fabric bag, as for example, by pitch; if cord is used, it may be wound around, or may be woven into the 35 fabric bag. The filled bag and cardboard or cord casing is proportioned so as to slip loosely within the outer zinc receptacle, leaving a narrow space 5 between the outer surface of the cardboard web and the zinc 40 container 6. The cardboard webs are spaced as shown, preferably in wide 7 and narrow 8 channels. Within the wide channels is packed the electrolyte 9, up to the top of the fabric bag. Above the top of fabric bag is 45 an air space 10, and then is placed a parafined or waterproof cardboard or thin wood partition 11 which fits very tightly around the carbon electrode 1 and also within the zinc container 6. Above the partition is provided a layer of a viscous water-sealing substance, such as a heavy oil 12, etc.; above the 50 oil is a second partition 13, and above this the usual layer of pitch 14, through which the carbon contact 15 projects. A vent 16 55 is provided, projecting through the top of

the cell down into the air space 10, consisting of a tube filled with a suitable porous material, such as gauze, etc., to provide an escape for any gases which may be evolved.

The electrolyte 9 consists of a mixture of 60 a powdered starch, such as corn starch, ammonium chloride, zinc chloride, and sodium bicarbonate, in proportions which may be varied, but I have found the following to be operative: 50 to 60% by volume of corn 65 starch, 20 to 18% by volume of ammonium chloride, 15 to 12% by volume of zinc chloride, 15 to 10% by volume of sodium bicarbonate.

To the electrolyte mixture is added sufficient water to moisten the mass to the consistency of a paste, which is then packed in the wide spaces 7 against the fabric bag and the zinc container, leaving the air spaces 8 empty. During use, the electrolyte mixture 75 expands and spreads through the space 5 into the air spaces 8 attacking fresh zinc surfaces, and thereby prolonging the useful life of the cell.

I claim:

1. A dry cell comprising a metal container serving as an electrode, a carbon electrode therein, a depolarizing mass comprising carbon, graphite, and manganese dioxide, partitions between the depolarizing mass and 85 the metal container, spaced bodies of electrolyte between said partitions, a space between said partitions and the metal container, said space providing room for the expansion of 90 said electrolyte.

2. A dry cell comprising a metal container serving as an electrode, a carbon electrode and depolarizing mass therein, said mass spaced from said container, partitions between the said mass and the container providing a plurality of spaces, an air space above the mass of depolarizer and a vent 95 extending from said air space to the outside of the cell.

3. A dry cell comprising electrodes and 100 an electrolyte, a plurality of compartments within the cell adjacent the outer wall, electrolyte in some of said compartments, and spaces providing a passage for said electrolyte to expand into unoccupied compartments. 105

In testimony whereof I hereby affix my signature.

P. A. BARBOSA.
